UNITED STATES PATENT OFFICE.

CARL R. GREEN, OF DAYTON, OHIO, ASSIGNOR TO THE NATIONAL VACUUM CLEANING COMPANY, OF DAYTON, OHIO, A CORPORATION OF OHIO.

PUMP.

937,790.

Specification of Letters Patent.

Patented Oct. 26, 1909.

Application filed February 20, 1908. Serial No. 416,855.

To all whom it may concern:

Be it known that I, CARL R. GREEN, a citizen of the United States, residing at Dayton, in the county of Montgomery and 5 State of Ohio, have invented certain new and useful Improvements in Pumps, of which the following is a specification.

My invention relates to pumps and particularly to air or vacuum pumps for use in 10 vacuum cleaning systems.

The object of the invention is to greatly simplify the structure as well as the means and mode of operation of such devices whereby they will not only be cheapened in construction, but will be more efficient and positive in operation, more easily operated, and unlikely to get out of repair.

With the above primary and other incidental objects in view as will more fully appear from the specification, the invention 20 consists of the means, mechanism, parts, construction, or their equivalents, and the mode of operation hereinafter described and set forth in the claims.

25 In the drawings Figure 1 is a plan view of an assembled double cylinder pump, embodying the invention. Fig. 2 is a side elevation of same. Fig. 3 is a vertical sectional view through the cylinder and valve chamber. Fig. 4 is a side elevation of a portion of one of the cylinders. Figs. 5 and 6 are detail transverse sectional views through the valve and valve chamber showing the relation of the inlet and outlet ports. Fig. 35 7 is a detail perspective view of the rotary valve.

Like parts are indicated by similar characters of reference throughout the several views.

40 In the drawings the pump is illustrated as being of the double cylinder type, but it is to be understood that the construction of each cylinder and operating mechanism is the same, and that the same constructions 45 hereinafter described may be used in a single cylinder pump.

In constructing the device there is employed a base 1, said base having bearings therein for the usual crank shaft 2. Mounted on the base 1 is one or more cylinders 3, according to the desired capacity of the machine. In each of the cylinders is located a reciprocating piston 4 of ordinary construction, operated from the crank shaft 2 55 in the usual manner.

Secured to each of the cylinders 3 is a cylinder head 5, having formed therein a cylindrical valve chamber 6. An inlet port 7 and an outlet port 8 form a means of communication between the interior of the cylinder 3 and the valve chamber 6, said ports extending through the cylinder head 5 at either side of the medial line of the cylinder. Connected to opposite ends of the valve chamber 6, is an inlet elbow member 9 connecting with the intake conduit, and an outlet elbow member 10, forming a discharge orifice.

Revolvably mounted within the valve chamber 6 is a hollow cylindrical valve 11, 70 divided into an intake compartment 12 and an outlet compartment 13 by a central wall or septum 14.

In each of the inlet and outlet compartments 12 and 13 are openings or ports 15 75 and 16 respectively, registering with the respective inlet and outlet ports 7 and 8 in the cylinder head 5. The ports 15 and 16 are so located in the valve 11 as to be brought alternately into registry with the ports 7 80 and 8 upon the continued rotation of the valve 11 within the chamber 6.

The relative positions of the ports 15 and 16 are shown in Figs. 5 and 6, which are transverse sectional views through the valve 85 and valve chamber, taken through the respective ports, the valve being rotated in the direction indicated by the arrows. It will be noticed that as positioned in the said views both the inlet and outlet ports are 90 closed, the outlet having been cut off while the inlet is approaching open position. This is the position of the valves as the piston 4 begins its return or intake stroke.

When the piston 4 reaches the lower or 95 inner intake limit of its stroke, the air within the cylinder will be below atmospheric pressure, and if the outlet port was open at this time the air would rush into the cylinder through said outlet opening. However the relative location of the ports 15 100 and 16 in the valve 11 is such that the outlet port is not opened until the piston 4 has traveled a sufficient distance on its return stroke to compress the air in the cylinder to 105 atmospheric pressure, at which time the outlet port will open and remain so throughout the remainder of the stroke. When the piston 4 has reached the limit of its upward or expelling stroke, the outlet valve will be 110

closed and the inlet opened by the rotation of the valve 11 which is rotated in unison with the crank shaft 2.

To drive the valve 11 a shaft 17 is provided, which projects laterally through the outlet elbow member 10, and carries a sprocket wheel 18 driven by a chain 19 from a similar sprocket 20 on the crank shaft 2. It is obvious that other equivalent means as 10 pulleys and belts or bevel gears might be employed for driving the valve, or a crank and pitman connection between the crank shaft and valve might be used, but the construction illustrated in the drawing is the 15 preferable device. The valve shaft 17 is shown as attached to the wall or septum 14 of the valve, however it is obvious that a head or spider might be formed at the extremity of the valve to form a connection 20 for said shaft 17.

Supported on the member 10 is pendent portion 21 having a slot 22 therein in which is adjustably secured an idler pulley 23 bearing on the drive chain 19 and by its adjustment serving to take up the slack in said chain.

In mounting the cylinders in duplicate the heads 5 are preferably located thereon in reverse order, as shown in Fig. 1 to economize 30 space. In this position the respective valve chambers and their connections to the intake conduit will overlap, or extend past the central line of the structure, in which combination the mean ends of the respective 35 valves will be the intake ends, and the extreme ends will be the outlets.

The inlet elbow members 9 are connected by a Y member 24 forming the terminal of the intake conduit, which is connected to the 40 Y member at 25. Thus a common intake conduit will be employed for both cylinders of the combination, the Y member 25 occupying a diagonal position, due to the overlapping ends of the valve chamber as before 45 mentioned.

This arrangement of parts will result in a very compact structure, which is very desirable in machines of the type described.

From the above description it will be apparent that there is thus produced a machine of the character described, which possesses the particular features of advantage before enumerated as desirable, but which obviously is susceptible of modification in its 50 form proportion, detail construction, and arrangement of parts without departing from the principle involved or sacrificing any of its advantages.

Having thus described my invention I claim,

1. In a single acting vacuum pump, a cylinder, a reciprocating piston therein, a cylinder head having an integral chamber formed therein, two ports in the cylinder head forming means of communication between the cylinder and said chamber in the cylinder head, a valve member continuously rotating in one direction mounted in the cylinder head chamber, said valve member comprising a tubular body open at opposite ends 70 and having a transverse wall or septum located therein dividing said tubular body into two compartments, ports in the walls of the respective compartments of the valve member, said ports being located in unaligned 75 relation and adapted to alternately register with the ports in the cylinder head upon rotation of the valve member, and means to rotate said valve member, substantially as 80 specified.

2. In a machine of the character described, a cylinder, a reciprocating piston therein, a cylinder head having a single inlet and a single outlet port therein, a valve chamber mounted on the cylinder head, a continuously rotating tubular valve member mounted in said chamber, said valve member being divided into a supply compartment and an exhaust compartment, a single port in each of said compartments adapted to register 90 with the corresponding inlet and outlet ports of the cylinder head at different points in the rotation of said valve member, substantially as specified.

3. In a double vacuum pump as described, two cylinders arranged side by side, a reciprocating piston in each of said cylinders, a continuous rotating valve member for each of said cylinders controlling the inlet and outlet ports thereof, said valve members having an intake orifice in one end thereof and a discharge orifice in the opposite end thereof, the said valve members being so mounted on the cylinders, that the discharge orifices will be located at the extreme ends of the 105 respective valve members and the inlet orifices will be located at the mean ends thereof, and a supply pipe common to both said 110 valve members, substantially as specified.

In testimony whereof, I have hereunto set my hand this 10th day of February A. D. 1908.

CARL R. GREEN.
